UNITED STATES PATENT OFFICE.

WILLIAM A. FIELD, OF CHICAGO, ILLINOIS.

MACHINE FOR MAKING TWYERS.

SPECIFICATION forming part of Letters Patent No. 781,058, dated January 31, 1905.

Application filed February 7, 1903. Serial No. 142,282.

To all whom it may concern:

Be it known that I, WILLIAM A. FIELD, a citizen of the United States, residing at Chicago, in the county of Cook and State of Illinois, have invented certain new and useful Improvements in Machines for Making Twyers, of which the following is a specification.

My invention relates to machines for making twyers, and is especially concerned with apparatus of this general type for making twyers having bell-shaped or flaring mouths.

In making twyers the core-rods are permanently mounted in the mold and produce the twyer openings or passages in the twyer blocks or bodies when the bottom core-plate, upon which the mouth end of the twyers or molded block is supported, is detached from the mold, the core-rods being withdrawn from the molded block or twyer to leave the necessary channels or passages therein as the twyer is forced out of the mold. It is obvious that when it is desired to produce twyers having bell-shaped or flaring mouths the lower sections or ends of the cores must be correspondingly flared or enlarged to produce the desired shape in the mouths of the passages or channels and that therefore core-rods providing such flaring or bell-shaped mouths in the twyers or molded blocks cannot be withdrawn from the twyers in the usual manner.

The object of my invention is to provide apparatus for making twyers having bell-shaped or flaring mouths.

The invention consists in the matters hereinafter described, and pointed out in the claims.

In the accompanying drawings, which illustrate an apparatus embodying my invention and which form a part of this specification, Figure 1 is a vertical central sectional view of an ordinary twyer-mold provided with my improvements. Fig. 2 is a view similar to Fig. 1, but taken at a right angle to the view of that figure. Fig. 3 is a transverse sectional view on the line 3-3 of Fig. 1. Fig. 4 is a view similar to Fig. 2, but showing the parts for loosening the cones in secondary or lowered position. Fig. 5 is a detail view in elevation of one of the cones that may be em-

ployed. Fig. 6 is a detail view showing the cone-pulling plate partly in side elevation and partly in section. Fig. 7 is a top plan view of the bottom core-plate, and Fig. 8 is a sectional view of the same on the line 8-8 of Fig. 7.

Referring to the drawings by reference-letters, A denotes a suitable mold provided in its interior with a suitable number of core-rods a , which are united at their upper ends by a suitable head a' , secured to the mold by a suitable spider. In the present exemplification I provide for the use of nine of these core-rods, it being of course understood that any suitable number may be employed. The mold is somewhat flared at its lower end, where it is provided with a removable clamp a'' , which detachably supports the socket B. The clamp and socket are connected in any suitable manner, as by the shouldered construction shown in the drawings. The clamp is attached to the mold in any suitable manner, as by lugs on the latter passing within or under suitable projections a^3 on the frame, the clamp being turned on the mouth by means of a handle a^4 to connect and disconnect the interlocking parts. The socket B is circular in cross-section and at its upper end is of a diameter the same as that of the mouth of the mold. Near its upper end the socket is provided with an internal shoulder b , providing a seat for the bottom core-plate b' , which fits within and closes the mouth of the mold when the socket is locked thereto by the clamp. The plate b' , which is shown in detail in Figs. 7 and 8, is provided with a number of vertical channels or passages b^2 , corresponding to the number and arrangement of the core-rods employed and respectively in line with them when the parts are assembled.

The socket B is provided with an internal plunger C, which fits the bore of the socket and has movement therein toward and away from the core-plate b' . The plunger C is shown in detail in Fig. 6 and consists of a circular top c and downwardly-projecting body c' , being substantially of an inverted-cup shape and the body being adapted to form an extended bearing on the inner wall of the socket. The plate is provided with a series

of tapped openings c^2 , which receive threads on the lower reduced ends d of the cones D. The cones are preferably of the form shown in Fig. 5, being hollow for at least a portion 5 of their lengths to receive the lower ends of the core-rods and being disposed and arranged on the plunger C to correspond with the disposition and arrangement of these rods, as clearly shown in Figs. 2 and 4. The cones are 10 provided with straight sections or portions d' to slidably fit the openings b^2 in the core-plate b' , the straight sections being of sufficient length to effectively close these openings in all positions of the cones. The upper portions 15 of the cones are tapered toward their upper ends. The cones are preferably hollow throughout their entire length in order that no material of which the twyer are formed may lodge in them, but will readily pass through 20 and prevent their clogging. The socket B is also, preferably, provided with openings b^4 , whereby the material that may pass through the cones may be readily removed.

The plunger C is operated by any suitable 25 means. In the drawings I have shown a preferred form of means for this purpose consisting of an eccentric shaft E, supported in suitable bearings e and e' in the socket and connected by eccentric links e^2 to the plunger C. The shaft has a suitable handle e^3 for operating it.

The parts normally occupy the positions shown in Figs. 1 and 2, when the plunger C is elevated and rests against the under side of 30 the core-plate b' , which in turn rests in its seat in the socket and closes the mouth of the mold. The material for the twyer or molded block is then suitably pressed into the mold and around the cores, the core-rods being suitably mounted in the mold. When the mold 35 is filled, the handle e^3 is moved sufficiently to draw the cone-pulling plunger C down to the position of Fig. 4, whereby the cones D are retracted and loosened from the material composing the twyer or block. The socket B is then unclamped from the mold and lowered by any suitable means, such as a vertically-movable shaft seated in the lower end b^3 of the socket carrying with it the core-plate 40 b' , the molded block or twyer, the plunger, and the core-cones D, the twyer being forced or pressed out and leaving the core-rods in the mold, thereby producing the necessary channels or passages in the twyer-body. The 45 molded block or twyer is removed from the core-plate b' , which may readily be accomplished without injury to the bell-shaped or flaring mouths of the twyer by reason of the preliminary loosening of the cones from the material surrounding the mouths while the 50 material was compressed against displacement or distortion in the mold. The socket B, carrying the various instrumentalities, is then again locked to the mold for another opera-

tion. It is obvious that the withdrawal or 65 retraction of the cones D from the bell-shaped mouths of the twyer may be accomplished either before or after the parts are unclamped and lowered from the mold, though in practice I prefer to perform this step while the 70 material is in the mold, as the mold then prevents the material from breaking or crumpling.

Having described my invention, I claim—

1. A sectional core for twyer-molds, comprising an upper core-rod and a lower individual cone adapted to receive the lower end of the rod. 75
2. In a twyer-machine, the combination with a mold, and core-rods, of a socket adapted to the mold, and movable cones in the socket and about the lower ends of the rods. 80
3. In a twyer-machine, the combination with a mold, and core-rods, of a socket detachable from the mold, a perforated core-plate in the 85 socket and normally closing the mold, and a series of cones movably mounted in the perforations of the plate and surrounding the lower ends of the rods. 90
4. In a twyer-machine, the combination with a mold, and core-rods, of a socket adapted to be clamped to the mold, a perforated core-plate in the socket and normally closing the mold, a plate movable in the socket toward and away from the core-plate, and a series of 95 cones attached to the movable plate and projecting through the core-plate to receive the ends of the core-rods. 100
5. In a twyer-machine, the combination with a mold, and core-rods, of a socket detachably secured to the mold, a perforated core-plate in the socket to normally close the mold, a series of hollow cones in the perforations of the core-plate and receiving the ends of the core-rods, a cone-plate in the socket carrying 105 the said cones, and an eccentric shaft in the socket connected to said cone-plate. 110
6. In a twyer-machine, the combination with a mold, and core-rods mounted therein, of a socket detachably connected to the mold, and cones movably mounted in the socket about the lower ends of the rods and adapted to be retracted on the rods independent of the socket and to be withdrawn from the rods when the socket is detached. 115
7. In a twyer-machine, the combination with a mold, core-rods mounted therein, and a perforated core-plate closing the mold, of cones in the perforations and receiving the lower ends of the rods, means to retract the cones, 120 and means to withdraw the core-plate and cones from the mold. 125
8. In a twyer-machine, the combination with a mold, core-rods mounted therein, of a socket detachably connected to the mold, a perforated core-plate in the socket and adapted to close the mold, a plunger movable in the socket, and a series of cones carried by the

plunger and disposed to form continuations of the core-rods when the parts are assembled.

9. In a twyer-machine, the combination with a mold and core-rod, of a socket detachably connected to the mold, a plunger in the socket, and a series of removable cones on the plunger.

In testimony whereof I affix my signature in presence of two witnesses.

WILLIAM A. FIELD.
